IRWIN F. KEPLER, OF AKRON, OHIO, ASSIGNOR TO THE B. F. GOODRICH COMPANY, OF NEW YORK, N. Y., A CORPORATION OF NEW YORK.

WATER BOTTLE OR BAG.

1,074,269.

Specification of Letters Patent.

Patented Sept. 30, 1913.

Application filed June 25, 1912. Serial No. 705,789.

To all whom it may concern:

Be it known that I, IRWIN F. KEPLER, a citizen of the United States, residing at Akron, in the county of Summit and State 5 of Ohio, have invented certain new and useful Improvements in Water Bottles or Bags, of which the following is a specification.

My present invention pertains to an improved water-bottle or bag, and has to deal 10 more particularly with the manner or method of securing the component parts of the bottle together.

The invention is illustrated in the annexed drawings, wherein:

15 Figure 1 is a side elevation of a bottle or bag constructed in accordance with my invention; Fig. 2 an enlarged sectional elevation of the upper portion of the bag and funnel, illustrating certain features of the 20 construction; Fig. 3 a vertical sectional view of the same parts; Fig. 4 a like view of the lower end of the funnel; and Fig. 5 a similar view of the upper portion of the bottle or the neck thereof.

25 The main object of the present invention is to produce a bottle which may be readily made, and to insure a tight joint between the bottle or the bottle-neck and the funnel, which, under my present invention, are 30 separately formed on account of the relative ease and cheapness of manufacture.

Referring to the drawings, 1 denotes the body of the bottle or bag, provided with an upstanding collar 2, having an inwardly-projecting annular flange 3 at the junction 35 of the body and collar, and likewise having at a point above said flange an inwardly-projecting rib or ring-shaped member 4. The body and the parts just referred to will 40 be formed independently of the funnel and its parts and will be fully vulcanized prior to their assembly with said funnel.

The funnel is designated by 5, and is formed with a downwardly-extending neck 45 6 in which is placed (and vulcanized in position) a threaded nipple 7, having a valve-seat 7^a, adapted to receive the usual screw plug or valve. The neck is provided upon its exterior face with an annular seat 50 or groove 8. Extending down from the funnel and formed as an integral part thereof is a skirt or apron 9, said skirt being spaced away from the neck to admit of the insertion of the collar 2 between said skirt and neck 6. 55 When it is desired to assemble the parts,

the inner surface of the collar will be covered with self-curing cement, or the neck will be so treated, and the neck forced down into the collar, at which time rib 4 will enter groove 8 and flange 3 will come into contact with the lower end of the neck, see Fig. 3. This arrangement forms an interlock between the two parts, and to securely hold them in place I preferably wind a narrow strip of friction cloth 10 about 60 the collar and then force and hold the parts in close relation by a piece of wire 11, drawn and secured around the collar and the overlying strip 10. To facilitate such operation, the skirt or apron 9 will preferably 65 be turned back, see dotted lines Fig. 4. After the parts are thus secured, a dose of self-curing cement will be applied to the outer face of the collar and the apron 9 turned down over the same, covering the 70 strip 10 and wire 11.

The inwardly-projecting flange 3 underlies the lower end of the neck, see Fig. 3, and serves to prevent the self-curing material from running out between the neck and collar, and likewise produces a longer line 80 of contact between said parts, as well as cutting off direct access of water to the joint between the collar and neck. It likewise strengthens the bottle at the point or line 85 of juncture between the body and collar.

The lower extremity of the apron will 90 preferably be beveled as shown, in order to produce a neat finish.

The completed bottle or bag shows no 95 seam and in use has been found highly efficient.

Having thus described my invention, what I claim is:

1. In a water-bottle, the combination of a body provided with a collar; a funnel section having a depending neck adapted to fit within said collar, said neck being of a thickness substantially equal to that of the collar; a threaded nipple carried by said neck, the nipple being of a diameter substantially equal to the interior diameter of the lower portion of the funnel and serving to sustain the neck against inward pressure; and means carried by said collar and neck adapted to form an interlock between said parts when assembled. 100

2. In a water-bottle, the combination of a body provided with a collar; a rib formed upon the inner face of said collar; a fun- 110

nel section provided with a depending neck, said neck being of a thickness substantially equal to that of the collar and having an annular groove formed upon the outer face thereof, the neck and groove making a close fit with the collar and rib aforesaid; and a nipple mounted within the neck, said nipple being of a diameter substantially equal to the internal diameter of the lower portion of the funnel and sustaining the neck against inward pressure.

3. In a water-bottle, the combination of a body provided with an upstanding collar; and a funnel having a depending portion, composed of two annular members having a spaced relation, and adapted to receive and embrace said collar.

4. In a water-bottle, the combination of a body having an upstanding collar; a funnel having a depending portion composed of two annular members having a spaced relation and adapted to receive and embrace said collar; and means carried by said collar and depending portion to form an interlocking connection between the same.

5. In a water-bottle, the combination of a body having an upstanding collar; an inwardly-extending flange formed at the base of the collar; an annular rib formed upon the inner face of the collar; a funnel; a depending neck formed upon said funnel,

said neck having an annular groove formed in the outer face thereof adapted to receive the rib aforesaid when the parts are assembled and the flange above specified contacts with the lower end of the neck; and a skirt extending downwardly from the funnel and adapted to cover the collar.

6. In a water-bottle, the combination of a body having an upstanding collar; an inwardly extending flange formed at the base of the collar; an annular rib formed upon the inner face of the collar; a funnel; a depending neck formed upon said funnel, said neck having an annular groove formed in the outer face thereof adapted to receive the rib aforesaid when the parts are assembled and the flange above specified contacts with the lower end of the neck; a strip of friction cloth wrapped around the neck; a binding wire secured in place over said strip, and a skirt extending downwardly from the funnel and adapted to cover the collar.

In testimony whereof I have signed my name to this specification in the presence of two subscribing witnesses.

IRWIN F. KEPLER.
